CARPET GRIPPER

Harvey J. Hill, Monterey Park, Calif., assignor to Roberts Manufacturing Co., Los Angeles, Calif., a corporation of California

Application October 19, 1956, Serial No. 617,095

1 Claim. (Cl. 16—16)

This invention relates to gripper strips for installing wall-to-wall carpeting and the like and, in particular, to a carpet gripper strip adapted for rapid and easy installation, especially in poorly illuminated locations such as corners, closets and the like.

Carpet grippers having sloping carpet engaging means with the points thereof directed toward one edge of the gripper strip are installed at the junction of a wall and the floor with the points directed towards the wall. In making such an installation, it has been necessary to feel the points or visually inspect the slant of the pins in order to properly orient the carpet gripper prior to nailing in place. The floors of rooms, especially corners and closets, are dimly lit and what illumination is available is usually partially obscured by the installer, resulting in loss of time, eye fatigue, missed and bent nails and misaligned or reversed gripper strips. These problems become more vexing when short pieces of carpet gripper are being used to complete the installation.

It is an object of the invention to provide a carpet gripper which is easily, rapidly and accurately installed in both well and poorly illuminated locations and in long or short lengths with a minimum of fatigue on the part of the installer. It is a further object of the invention to provide a carpet gripper strip having longitudinal bands of contrasting colors to indicate proper orientation of the strip. A further object of the invention is to provide a carpet gripper having preset mounting nails which are of a color contrasting with the color of the strip against which they are viewed.

It is another object of the invention to provide a carpet gripper having pre-set mounting nails which are so located as to produce maximum strength in the completed installation.

While much carpet gripper stripping is provided with pre-set mounting nails, some stripping is not. Furthermore, the ends of lengths of carpet gripper which have been cut to a particular size and short lengths of carpet gripper require the use of additional nails for fixing the gripper to the floor. It is an object of the invention to provide a carpet gripper strip having a shallow groove in the upper surface thereof extending longitudinally along the strip at the location where mounting nails are to be inserted, thereby assuring proper location of mounting nails inserted by the installer.

The invention also comprises novel details of construction and novel combinations and arrangements of components, which will more fully appear in the course of the following description. The drawing shows a preferred embodiment of the present invention which is given by way of illustration and example.

In the drawing:

Fig. 1 is an isometric view of a length of carpet gripper embodying the teachings of the invention;

Fig. 2 is a sectional view taken along the line 2—2 of Fig. 1; and

Fig. 3 is a sectional view showing the carpet gripper of the invention in use gripping a carpet.

2

The carpet gripper of the invention includes a relatively long and narrow strip 10 of a thin material such as plywood, aluminum or the like. A plurality of carpet hooking nails 11 are set in the strip 10 with pointed ends 12 of the nails 11 extending upward from the top surface of the strip 10. All of the pointed ends 12 are preferably oriented in the same direction, being to the left or wall edge 13 of the strip shown in Fig. 2.

Longitudinally extending color bands 16 and 17 are provided on the top surface of the strip 10, the band 16 being located away from the wall edge 13 of the strip and preferably extending over not more than one-half the width of the strip. The bands are of contrasting colors and it is preferred that the contrast be one of value rather than of hue, or color intensity, since such a value contrast is normally more harmonious, more readily seen under poor lighting conditions and produces less visual distraction and strain on the eyes than does hue or intensity contrast. In the preferred embodiment of the invention illustrated herein, where the strip 10 is composed of plywood, the band 17 may be the natural light brown color of the wood and the band 16 may be a dark brown paint applied to the top surface of the strip by conventional methods.

While the bands of color on the carpet gripper of the invention have been illustrated in the drawing as being solid, this is not necessary to the practice of the invention. A band of color may include lettering, a design, a stippled or polka dot pattern, or the like. When the gripper strip 30 is made of wood, a color band having local variations in color due to the grain of the wood may be obtained. Therefore the term "color band" is intended to include an area over which the coloring may vary but which produces the visual effect of a band of color.

35 A plurality of mounting nails 20 are spaced longitudinally along the strip 10 with the nails imbedded into the strip through the upper surface thereof. These mounting nails are colored to contrast with the color of the band 17, the nails being dark blue or black in the preferred embodiment of the invention having the natural light brown wood color for the band 17.

It has been found that the maximum strength of the installed carpet gripper is obtained when the mounting nails 20 are positioned along a line at 40 percent of the width of the strip measured from the wall edge 13. Furthermore, it has been found that the strength decreases very rapidly when this figure is made smaller, whereas the strength decreases at a moderate rate as the position is moved away from the wall edge. Therefore, it is preferred to always locate the mounting nails more than one-third but less than two-thirds of the width of the strip as measured from the wall edge and preferably within a zone defined by lines at 35 and 50 percent of the width of the strip, measured from the wall edge 13.

55 A longitudinally extending shallow groove 22 is located in the top surface of the strip 10 along the preferred location line for the mounting nails.

The carpet gripper of the invention may be used in installing wall-to-wall carpeting by placing the strip on a floor 24 (Fig. 3) with the wall edge 13 spaced slightly from a wall 25, the wall edge preferably being beveled to provide clearance for dirt and irregularities appearing at the junction of the floor 24 and wall 25 and to provide a wedging grip on the edge of the carpet. A rug pad 26 is customarily placed on the floor 24 and a carpet 27 is laid over the pad 26 and engaged with the nails 11 by well known methods, the raw edge of the carpet being forced into the gap between the wall edge 13 of the gripper and the wall 25.

70 The orientation of the carpet gripper strip relative to the wall may be determined by visually inspecting or by feeling the pointed ends 12 of the nails 11. This is a

tedious and time consuming operation and when performed over an eight hour day, produces many a sore finger. However, with the carpet gripper strip of the invention, the installer need only note the position of the colored bands in order to properly orient the strip. Since the bands are of strongly contrasting colors, this form of construction is equally usable with long and short lengths of carpet gripper strip and in dimly lit locations.

When installing carpet gripper in dimly lit locations, trouble is often encountered with properly driving the mounting nails, the nails often being bent over and occasionally being missed. With the carpet gripper strip of the invention, where the nails are of a color contrasting with the surface of the strip against which they are viewed, as seen in Fig. 1, the likelihood of bent or missed nails is materially reduced and, accordingly, the speed of installation may be increased. Tests have indicated that the installation time under good lighting conditions for carpet gripper embodying the invention is in the order of six percent less than that for conventional carpet gripper and that under one particular set of poor lighting conditions, there is a reduction of more than twenty percent.

At corners and around irregular shapes, where short lengths of carpet gripper are often used, the saving of time and effort is especially noted. It is often necessary to use additional mounting nails to supplement those pre-mounted in the strip in installing the carpet gripper. Such additional nails may be used at the end of a strip and in short strips which have one or no pre-mounted nails therein. The groove 22 serves as a locating means for properly positioning the nails relative to the edges of the strip and the nails may be positioned in the groove entirely by feel. Such a groove does not require a particular size of nail and, being very shallow, does not

materially alter the strength of the completed installation.

It is clear that some features of the invention can be used independently of others and that the invention is capable of a variety of embodiments. The invention is not to be limited to the specific embodiment disclosed herein but as defined in the following claim.

I claim as my invention:

In a carpet gripper suitable for installation in both long and short strips, the combination of: a long and narrow strip of a relatively light colored material, said strip having an upper surface provided with a longitudinal band adjacent one edge and of a relatively dark color, said upper surface having a shallow groove extending longitudinally therealong parallel to an edge of said strip whereby installation nails may be driven through said strip at said groove at any point along said strip; a plurality of spaced nails projecting into said strip through said groove and extending thereabove, said nails being of a dark color contrasting with the color of said material; and a plurality of carpet hooking means having pointed ends projecting upward from said strip.
